UNITED STATES PATENT OFFICE.

CHARLES M. SUTTLE, OF WICHITA, KANSAS.

WEATHER STRIPPING.

Application filed December 10, 1925. Serial No. 74,566.

This invention relates to improvements in weatherstripping, having for an object to provide a novel and highly efficient form of weatherstripping for sliding window sashes, whereby the same will be proofed against the passage of cold air, water, snow, soot and other undesirable matter thereby and additionally, will be afforded means which will effectually serve to insure free and unbinding sliding movement of an equipped sash, irrespective of shrinkage or swelling of the same under influence of different atmospherical conditions, the weatherstrip construction being such that it will provide a constant bearing pressure or tension and contact upon and with the sash and by consequence, will at all times serve to cushion the same hence maintaining the sash constantly in proper position for sliding movement in its frame and holding it against objectionable relative movement with varying atmospherical conditions, as well as avoiding rattling or vibration thereof.

It is an equally important object of the invention to provide a weatherstripping of the character mentioned which may be advantageously used upon the sides, tops and bottoms of a sliding window sash, affording a sash so equipped with means for positively proofing the same against the passage of air or matter between it and the casing or frame therefor.

Yet another object of the invention may be stated to provide a weatherstripping which will serve as an effectual guide for an equipped sash during sliding of the same and which, is formed with a resilient contacting portion whereby a cushion-like contact between it and the adjacent marginal portions of a window sash will be constantly maintained.

Other objects of the invention will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a fragmentary, horizontal, transverse section through a sliding window sash equipped with the improved weatherstripping,

Figure 2 is a vertical or longitudinal fragmentary section through a window wherein the side thereof is equipped with the invention along its bottom or lower marginal portion,

Figure 3 is an end elevation of the improved weatherstripping,

Figure 4 is a similar view wherein the weatherstripping has been shown as being depressed by the application of pressure thereto from an engaged portion of a sliding window sash, the sash being fragmentally shown in dotted lines herein, and

Figure 5 is an end elevation of a slightly modified form of the weatherstripping.

Having more particular reference to the drawings, in connection with which like characters of reference indicate corresponding parts throughout, the improved weatherstripping may be stated to comprise a body portion formed of resilient or yieldable material, the material shown herein being sheet metal wherein such material is formed with oppositely disposed basal flanges or portions 80 1 and 2, constituting the body portion proper of the improved weatherstripping, while a longitudinally disposed angularly extending guide rib 3 is formed in this body portion of the weatherstripping by bending a part 85 thereof upon itself in a manner as is clearly illustrated in the Figure 3. In order that the basal portion or flange 1 of the body of the weatherstripping may be provided with means, resilient or yieldable in nature, which 90 will maintain a constant pressure or tensioning contact with an adjacent marginal portion of a sliding window sash, said portion is formed with an upstruck or bent transversely curved portion 4 longitudinally 95 throughout its entire length, it being noted that the said transversely curved portion 4 is formed intermediately of the opposite sides of the basal flange 1 and by consequence, that those portions of the flange 100 bordering said curved portion will form a supporting or contacting medium with the adjacent surface or portion of a window frame F receiving the stripping, while the transversely curved portion 4 will be maintained away from said surface of the frame F and by consequence, will provide the weatherstripping with a cushioning like engaging or contacting means adapted to contact or engage with an adjacent marginal portion of an equipped window sash S. In 110 this fashion, it will be appreciated that the

110

utility or efficiency of the transversely curved spring or cushioning portion 4 will in no way be affected by the presence of the angularly disposed longitudinally extending guide rib 3.

The basal portion or flange 2 upon the opposite side of the guide rib 3 is disposed at an obtuse angle with respect to the adjacent side of said rib 3 as is shown in the Figure 3, 10 the outer side or marginal portion of the basal flange 2 being arranged in a plane corresponding to that in which the outer portion of the flange 1 is arranged; hence, affording the completed weatherstripping 15 with a supporting surface which will insure proper positioning of the longitudinally disposed guide rib 3 with respect to the receiving groove *g* therefor formed in the adjacent marginal portion of the equipped sliding 20 window sash S.

In equipping or installing the improved weatherstripping in or upon a window equipped with a sliding sash such as is shown herein, a driven headed, screw-threaded or similar fastening device or devices is 25 or are passed through the outer portion of the basal flange 1 as is indicated by the numeral 5, such fasteners being engaged in adjacent portions of the window frame F and hence, properly locating the weatherstripping with respect to the coacting marginal portion of the equipped window sash S and further, preventing relative movement as 30 between such weatherstripping and the frame F or the sash S. It will be thus seen that while this particularly anchored portion of the body of the weatherstripping will be held against movement, the opposite side or basal portion 2 thereof will be permitted of 35 a comparatively limited sliding movement with respect to the supporting or receiving surface of the window frame F, as is indicated in the Figures 1 and 2. In those instances where the weatherstripping is attached to the opposite side of the window 40 sash S, certain of the window frame guide strips *e* are rabbeted as is indicated by the numeral 6, hence, permitting a free or sliding portion of the basal flange 2 to be mov- 45 ably engaged therein as is clearly shown in the Figure 1. In this particular adaption or usage of the weatherstripping, the opposite sides or marginal portions of the equipped window sash S are formed with the grooves 50 *g* longitudinally throughout their respective lengths and into these grooves *g*, the longitudinally disposed guide ribs 3 of the weatherstripping are slidably introduced; the formation of the guide ribs 3 being such as 55 to insure a slight frictional contact as between the side walls of the engaged grooves *g*, whereby to prevent relative movement of this particular point, while the outwardly curved portions 4 of the basal flange 1 con- 60 tact with an adjacent portion of the corre-

sponding margin or side of the window sash S as is clearly shown in the said Figure 1; the opposite basal portion or flange 2 contacting with a part of the corresponding guide of the window sash S, while the free 70 outer side or margin thereof has sliding or movable engagement with the adjacent portion of the window frame F receiving such guide. By reason of this contact as between the transversely or outwardly curved portion 4 of the basal flange 1 with the adjacent marginal portion of the window sash S, it will be understood that a constant pressure or tension and contact will be had upon and with the adjacent portion of the window sash 75 S, thereby positively proofing the same against the admission of air or matter by it, that is, between it and the frame F receiving the same. Likewise, this constantly applied pressure, tension and contact will serve as 80 means for effectually bringing about the proper positioning of the slidable window sash in the frame F whereby said sash will be at all times permitted of free and unbinding sliding movement. Likewise, be- 85 cause of this peculiar mode of engagement as between the weatherstripping and the slidable sash S, it will be appreciated that the weatherstripping will compensate for shrinkage or swelling of the sash S or its frame F by reason of the subjection of the same to different or varying atmospherical conditions. Consequently upon this, the window sash S will not only be constantly main- 90 tained in position for free and unbinding 95 sliding movement in the frame F but likewise, said sash will be held positively against relative movement with respect to said frame and against objectionable vibration or rattling. The guide 3 sliding within the groove 100 *g* of the window sash S will serve not only as a weathersealing or proofing means for the equipped sash, but likewise, will serve to insure as above inferred, the maintenance 105 of said sash in proper position with the weatherstripping and with the frame F at all times.

With adaption or arrangement of the improved weatherstripping to the bottom or top marginal portions of a sliding sash S, 110 the weatherstripping is similarly anchored or secured to the receiving frame F therefor, in positions to be engaged by the upper or lower marginal portions of the sash S when such sash is slid into engagement therewith. Upon contact of an equipped sash S with the weatherstripping in this particular adaption thereof, the transversely curved portion 4 of the basal flange 1 will be flexed upon itself and by reason of the tension so applied there- 115 to, a positive weatherproofing contact will be established as between it and the adjacent or contacting marginal portion of the sash S. Likewise, the adjacent marginal portion of 120 said sash S is formed with its groove *g*, cor- 125 130

responding to the grooves g aforesaid, and into this groove g' , the angularly disposed, longitudinally extending guide rib 3 is slidably engaged, thus offering a further proofing or sealing means for the resultant connection or jointure.

In the Figure 5, I have shown a slightly modified form of the improved weatherstripping. Herein, the weatherstripping is constructed of material corresponding to that from which the weatherstripping shown in the preceding embodiment is formed; the device including basal portions or flanges 1' and 2' while an angularly disposed longitudinally extending guide rib 3' is formed between the flange portions 1' and 2'. The basal flange 1' is provided with a longitudinally disposed transversely curved portion 4' arranged intermediately of the opposite side of said basal flange, while the basal flange 2' is formed with a transversely curved longitudinally extending portion 7 throughout its entire length, thus, affording said basal flange 2 with a spring or resilient or cushioning contact means engageable with an adjacent marginal portion of an equipped sash S and insuring the maintenance of a complete weatherproofing contact or engagement as between the same and said equipped sash S as well as maintaining a constant pressure or tension thereupon. This formation of the transversely curved longitudinally extending portion 7, will, as will be understood, accentuate the application of the position retaining pressure exerted by the transversely curved longitudinally extending portion 4' upon its particularly adjacent portion of the equipped sash S, and by consequence, it will be appreciated that said sash will be positively retained, at all times, in proper position with respect to the frame F receiving it.

At this point, it should be also noted that shoulders 8 and 9 are formed adjacent the basal portions of the opposite sides of the longitudinally disposed guide rib 3', between the same and its connection or jointure with the transversely curved longitudinally extending portions 4' and 7. These shoulders, which are arranged at somewhat obtuse angles with respect to the adjacent or opposite sides of the guide rib 3' will serve as means for further accentuating the spring or cushion like engagement of the weatherstripping with the adjacent marginal portion of an equipped or receiving sash S,

and furthermore, will permit of free or uninterrupted spring contact as between the opposite sides of the basal portion of the guide rib 3 and the adjacent side wall of the 60 groove g' receiving it.

Manifestly, the construction shown is capable of considerable modification and such modification as is within the scope of my claims, I consider within the spirit of 65 my invention.

I claim:

1. A weatherstripping formed from a single strip of spring metal including spaced basal portions and an intermediate portion 70 formed into an upstanding longitudinally disposed guide rib throughout the length of the strip, one of the basal portions having its intermediate portion bent outwardly through its length and curved transversely, 75 the other side of said basal portion beyond the transversely curved part being flat and normally arranged at an angle to the adjacent surface of a receiving frame and adapted to be freely slidable over the same, 80 and that side of said basal portion in proximity to the rib being inclined at an obtuse angle to the transversely curved part and to the adjacent side of the rib and being at times adapted to contact with the adjacent 85 surface of a receiving frame to increase the resiliency of the transversely curved part, the remaining basal portion on the opposite side of said guide rib being disposed at an obtuse angle with respect to the adjacent 90 side of said rib and at an angle to the adjacent surface of the receiving frame whereby to be freely slidable thereover, the free edge of said last mentioned basal portion being arranged in a plane approximately corresponding to that in which the plane portion of the first mentioned basal portion is arranged.

2. A weatherstripping as claimed in claim 1 wherein the last mentioned basal portion 100 is offset adjacent the rib and arranged at an inclination to the rib, and said inclined portion being symmetrical with respect to the inclined part of the other basal portion and being at times adapted to contact with the 105 adjacent surface of a receiving frame to increase the resiliency and efficiency of the strip.

In witness whereof I have hereunto set my hand.

CHARLES M. SUTTLE.
